Patented August 18, 1903.

UNITED STATES PATENT OFFICE.

AUGUSTUS H. HEISEY, OF PITTSBURG, PENNSYLVANIA.

DESIGN FOR A CANDELABRUM.

SPECIFICATION forming part of Design No. 36,500, dated August 18, 1903.

Application filed July 11, 1903. Serial No. 165,191. Term of patent 7 years.

To all whom it may concern:

Be it known that I, AUGUSTUS H. HEISEY, a resident of Pittsburgh, in the county of Allegheny and State of Pennsylvania, have invented a new, original, and ornamental Design in Candelabra; and I do hereby declare the following to be a full, clear, and exact description thereof.

The drawing illustrating my design contains a figure showing a perspective view of the candelabra.

What I claim is—

The ornamental design for candelabra as illustrated.

In testimony whereof I, the said AUGUSTUS H. HEISEY, have hereunto set my hand.

AUGUSTUS H. HEISEY.
